J. F. McELROY.
CAR DOOR SIGNAL SYSTEM.
APPLICATION FILED JULY 8, 1914.

1,172,377.

Patented Feb. 22, 1916.

UNITED STATES PATENT OFFICE.

JAMES F. McELROY, OF ALBANY, NEW YORK, ASSIGNOR TO CONSOLIDATED CAR HEATING COMPANY, A CORPORATION OF WEST VIRGINIA.

CAR-DOOR SIGNAL SYSTEM.

1,172,377.

Specification of Letters Patent. Patented Feb. 22, 1916.

Application filed July 8, 1914. Serial No. 849,657.

To all whom it may concern:

Be it known that I, JAMES F. McELROY, a citizen of the United States, residing at Albany, county of Albany, State of New York, have invented certain new and useful Improvements in Car-Door Signal Systems, the following being a full, clear, and exact disclosure of the one form of my invention which I at present deem preferable.

13 For a detailed description of the present form of my invention, reference may be had to the following specification and to the accompanying drawing, which illustrates my invention, wherein—

15 Figure 1 shows a diagram of my system and Fig. 2 a detail thereof.

My invention relates to a circuit-system for signaling to the motorman of a car or train the closure of the several doors thereof.

20 Referring to the drawing, A represents a line wire, shown in Fig. 1 as extending through the several cars of a train. The train may contain any desired number of cars although but two are represented in

25 Fig. 1. The line-wire will, however, serve equally well if it extends through only a single car. At each end of each car the line-wire A is connected to a switch B which has three positions corresponding to the three

30 contacts 1, 2 and 3 respectively. In its first position switch B connects with the trolley, which then serves as a source of current-supply for the line-wire, being connected thereto through a resistance R. In its

35 second position the switch B leaves its line-wire branch open-ended. In its third position the switch connects with a signal S, the opposite terminal of which is grounded. The switch B which is at the rear end of the

40 car or train will be turned to connect with the trolley, while that one at the head of the train will be turned to connect with signal S, the opposite terminal of which is grounded. The intermediate switches B, in 45 the case of a train containing two or more cars, will be left open-ended. That disposition of the switches B is clearly indicated in Fig. 1 of the drawing.

From line-wire A a branch wire goes to 50 each of the respective doors of the car or train and is normally open at the door, so long as the door is closed, but is arranged to be closed when the door is opened. In Fig.

55 the door branch is shown as coming to the switch-lever 4, which is normally held away

from the corresponding contact 4 so long as the door E is closed, but brought, by spring D, into engagement therewith to close the circuit when the door is opened, thereby connecting the door branch to ground. 60

It is manifest that when all the doors are closed, the current from the trolley will go from the rear of the car or train through line-wire A to the signal S at the head of the car or train and so maintain the signal 65 in its normal energized condition. If, however, a single door is open, it will close its ground-branch and thereby short-circuit the signal S and cause it to be extinguished, giving notice to the motorman 70 that a door is open. Likewise, if the line-wire A becomes grounded by accident, as is liable to happen, it will, in a similar way, cause the extinction of the signal. The source of supply is connected to wire A at 75 the rear of the train in order that, if the train should break in two, it would cut-off the source of current and cause the extinction of the signal. Another advantage of my system is that it requires but a single 80 line-wire and a single branch-wire therefrom at each car-door. Another advantage is the elimination of the trouble, frequently encountered, of the failure of the motorman to turn the right connecting-up switch on a 85 train, with the result that the system, while apparently working rightly, will in fact be disconnected from the doors in one half or more of the cars of a train, and so be unaffected by the opening or closure of such 90 disconnected doors. In my system that cannot occur, for even if the motorman turns one of the intermediate switches B (instead of the rear switch B) to its trolley-connection, the doors of the entire train will still 95 maintain control of the signal.

What I claim as new and desire to secure by Letters Patent is:

1. In a car door signal, the combination with a line wire, and ground connections 100 therefor, of a source of current supply, means at one end of said line wire to selectively close the circuit to said source of power, or to said ground connections, a signal in each of the ground connections, and 105 normally open ground branches from said line wire corresponding to and controlled by the respective doors of the car.

2. In a car-door signal system, the combination with a line-wire in the car, of a 110

- source of current-supply therefor, a grounded signal, branch-wires extending to the several doors of the car, and means for grounding each of said branches on the opening of the corresponding door.
3. In a car-door signal system, the combination with a line-wire in the car, of a source of current-supply therefor, a normally-energized signal in a grounded branch of said line-wire, and normally-open ground-branches for each door adapted to be closed by the opening of the corresponding door.
4. In a car-door signal system, the combination with a line-wire in the car, a source of current-supply connected thereto at one end of the car, a normally grounded signal at the opposite end, and normally-open ground branches for the respective doors adapted to be closed on the opening of a door.
5. In a car-door signal system, the combination with a line-wire in the car, of a source of current-supply and a grounded signal at each end of the car, switches at each end of the car for connecting the line-wire to the source of supply at one end and to the grounded signal at the other end, and branch ground-wires controlled by the respective doors of the car.
6. In a car-door signal system, the com-

bination with a line-wire in the car, of a source of current-supply and a signal in series in said line-wire, ground-connections for each end of said line-wire, normally-open ground branches from said line-wire, and a circuit breaker in each ground branch controlled by a car door so as to be closed by the opening of the door.

7. In a car-door signal system, the combination with a line-wire extending through two or more cars of a train, of a branch therefrom at each end of each car, a switch in each of said branches having three positions, one position serving to connect the branch to ground through a signal, another position serving to connect the branch to a source of current-supply, and the third position serving to open-end the branch, and a normally open ground-branch from said line-wire extending to each of several car-doors of the train and arranged to be closed by the opening of the corresponding door.

In witness whereof I have hereunto set my hand, before two subscribing witnesses, this 6th day of July 1914.

JAMES F. McELROY.
